G. E. BALL

BEVERAGE MIXER

Filed April 13, 1923

Inventor:
George E. Ball,
by his attorney,
Charles R. Searle.

UNITED STATES PATENT OFFICE.

GEORGE E. BALL, OF BRIDGEPORT, CONNECTICUT, ASSIGNOR TO WHITING MANUFACTURING COMPANY, OF BRIDGEPORT, CONNECTICUT, A CORPORATION OF NEW YORK.

BEVERAGE MIXER.

Application filed April 13, 1923. Serial No. 631,799.

To all whom it may concern:

Be it known that I, GEORGE E. BALL, a citizen of the United States, residing at Bridgeport, in the county of Fairfield and State of Connecticut, have invented a certain new and useful Improvement in Beverage Mixers, of which the following is a specification.

The invention relates to containers adapted to receive the liquids to be mixed and to be shaken to produce the required thorough mixture, and the object of the invention is to provide a device of this character in which the introduction of the contents, and the shaking, straining and pouring operations are easily performed without danger of waste or damage by leakage.

Another important object is to provide means for sealing the container against the escape of the contents during the shaking operation, and for readily releasing the seal to permit the liquid contents to be poured without removing any of the parts of the container.

The invention consists in certain novel features and details of construction and arrangement by which the above objects are attained, to be hereinafter described and claimed.

The accompanying drawings form a part of this specification and show the invention as it has been carried out in practice.

Figure 1 is a side elevation of a mixer or shaker embodying the invention.

Figure 2 is a corresponding front elevation.

Figure 3 is a plan view of the container neck and immediately adjacent parts, with the cover removed.

Figure 4 is a vertical central section taken on the line 4—4 in Figure 2.

Figure 5 is a plan view of the under face of the cover alone.

The remaining figures are on a larger scale.

Figure 6 is a front elevation of the cover, showing the straining perforations.

Figure 7 is a vertical section through the neck of the container, partly in elevation and showing a series of apertures arranged to coact with the perforations shown in the preceding figure.

Figure 8 is a rear elevation of the cover, showing the air-vent therein.

Figure 9 is a vertical section through the

neck of the container, partly in elevation and showing an air-opening adapted to coact with such air-vent.

Similar reference numerals indicate the same parts in all the figures.

The body of the container is marked 10 and is preferably of thin metal having a slightly tapered annular neck 11 flared upwardly and outwardly. At the junction of the neck with the body the latter is contracted inwardly to form an annular shoulder or seat 12, and on the seat, shown as at the rear of the neck, is a narrow upwardly projecting lug 13.

On the front of the neck is a pouring lip 14 curved upwardly and outwardly and in the neck within the lip 14 is a series of apertures 15 for the escape of liquid in the straining and pouring operation. A handle 16 is shown extending from the neck to the body at the rear, by which the container may be conveniently held.

The cover is marked 17 and is shown as a hollow plug of thin metal having a depending tapered annular flange or bezel 18 matching snugly to the interior of the neck 11, and having its upper portion domed and shaped to be conveniently grasped by the hand for removal or for partially rotating the bezel relatively to the neck.

The bezel 18 is of such depth as to rest upon the seat 12 when the cover is in proper frictional engagement with the neck, and is provided with a long notch at 19, shown as extending a little more than one quarter of the circumference, and matching the lug 13, the vertical edges of the bezel at the ends of the notch serving with the lug as stops 20 and 21 to strike the lug and limit the partial revolutions or oscillations of the cover in both directions.

Perforations 22 in the bezel at the front are arranged to register with the apertures 15 in the neck when presented thereto, and in the bezel opposite the perforations 22, is an air-vent 23 located to register with an air-opening 24 in the neck at the rear.

The contact of the lower edge of the bezel with the seat 12 determines the degree of frictional engagement of the bezel with the neck, and any looseness due to wear on the contacting surfaces of the bezel and neck will be compensated by corresponding wear between the edge of the bezel and the seat, which permits the bezel to sink a lit-

tle lower within the neck and thus maintain the desired snug fit between the tapered surfaces.

The materials to be mixed are introduced by removing the cover 17 which is then replaced with the lug 13 received in the notch 19 of the bezel, thus insuring proper insertion, and is turned until the stop at 20 strikes the lug; in this position the perforations 22 and air-vent 23 lie in contact with the solid portions of the neck 11 and the container is reliably sealed and, with light pressure of the operator's hand upon the cover to prevent it from becoming unseated, the contents may be safely shaken as required to effect the desired mixing. The cover is then partially rotated until the stop 21 strikes the lug 13 in which position the perforations 22 register with the apertures 15 and the air-vent 23 coincides with the air-opening 24. The liquid contents may then be poured from the lip 14, becoming strained in passing through the perforations 22 and apertures 15, by which any pieces of solid matter, as cracked ice, are retained; and the coincident air-vent 23 and air-opening 24 admit air to insure a steady uninterrupted flow from the lip.

The taper of the bezel and neck should be slight but sufficient to permit the cover to be removed readily, while also so truly cylindrical as to secure close contact of the contiguous surfaces to insure a tight seal and to maintain the strong frictional engagement necessary to prevent accidental loosening of the cover when the container is violently agitated in the shaking operation.

Modifications may be made in the forms and proportions, and parts of the invention may be used without the whole. The handle 16 may be omitted.

The improved mixer is neat and attractive in appearance, is simply and economically constructed in two parts, and is eminently efficient in operation.

I claim:—

1. In a device of the character set forth,

a container having a tapered neck with an internal annular seat, and a cover having a bezel correspondingly tapered and fitted to said neck and adapted when resting upon said seat to form a liquid seal between the neck and bezel, the tapered walls of the neck and bezel having cooperating apertures for the discharge of the liquid, and an air vent.

2. In a device of the character set forth, a container having a tapered neck with an internal annular seat, and a cover having a bezel correspondingly tapered and fitted to said neck and adapted when resting upon said seat to form a liquid seal between the neck and bezel, the tapered walls of the neck and bezel having cooperating apertures for the discharge of the liquid, and an air vent, and cooperating stop means on the cover and neck for limiting relative movement thereof.

3. In a device of the character set forth, a container having a tapered neck with an internal annular shoulder, a cover having a bezel correspondingly tapered and fitted to said neck and adapted when resting upon said shoulder to form a liquid seal between the neck and bezel, the tapered walls of the neck and bezel having cooperating apertures for the discharge of the liquid, and an air vent, and a pouring lip rigid with the neck of the container.

4. In a device of the character set forth, a container having a tapered neck with an internal annular seat, a cover having a bezel correspondingly tapered and fitted to said neck and adapted when resting upon said seat to form a liquid seal between the neck and bezel, the tapered walls of the neck and bezel having cooperating apertures for the discharge of the liquid, and an air vent, said neck having a lug and the bezel having a notch cooperating therewith to limit relative rotary movement of the cover and container.

In testimony that I claim the invention above set forth I affix my signature hereto.

GEORGE E. BALL.
